ABSTRACT: A removable coin holding means associated with a coin operated construction. The construction includes a permanent bracket and the coin holding means carries a fixture which is adapted to be slideably received by the bracket whereby the bracket will support the coin holding means. The bracket and fixture define aligned coin passages whereby coins deposited in the coin operated construction will be delivered to the coin holding means. A downturned lip is defined by the bracket, and the fixture defines a relieved portion whereby the fixture can clear the lip during insertion in the bracket and whereby the lip will thereafter serve as a blocking means to prevent insertion of any instrument between the bracket and fixture which could be used for purposes of pilfering.

REMOVABLE COIN HOLDING MEANS

SPECIFICATION

This invention relates to a coin holding means which can be associated with a coin operated construction. The coin holding means is removable whereby it can be used for collecting coins for a specified period, and then replaced with a new holding means.

In view of the fact that coin operated machines are in wide use, it has been necessary to devise systematic means for the handling of the coins. In a typical operation, a coin box or coin bag is associated with each machine. Attendants periodically service the machines, and one of their functions is to handle the coins. In some operations, this may simply comprise removal of the coins from the receptacle.

Difficulties have occurred with respect to coin operated machines due to a high incidence of pilfering. The collection of coins can be an extremely great source of temptation, particularly because it is difficult to monitor the machines. For various reasons, the actual revenue which a particular machine should obtain can vary considerably and, accordingly, if an attendant removes a portion of the coins when collecting, it is almost impossible to detect this.

For this reason, coin receptacles have been designed which substantially eliminate the possibility of surreptitious tampering. For example, Christensen U.S. Pat. Nos. 3,154,246 and 3,298,602 disclose in coin receptacles which are designed to prevent removal of the coins from the receptacles except by authorized persons. The coins could, of course, be removed by breaking open the receptacles; however, it is not possible to remove the coins without making it obvious that pilfering has occurred.

In the case of the structures described in the aforementioned patents, the coin receptacles are attached to brackets which form a permanent part of the coin operated machines. When an attendant removes a receptacle, he then inserts an empty receptacle for purposes of future collection.

It is a general object of this invention to provide an improved coin holding means which is adapted to be removably associated with coin operated machines and which includes additional safeguards against tampering.

It is a more specific object of this invention to provide a coin holding means which prevents surreptitious pilfering by attendants, particularly pilfering which might be attempted by preventing coins from entering a coin receptacle where the receptacle is mounted on a bracket carried by a coin operated machine.

These and other objects of this invention will appear hereinafter and for purposes of illustration, but not of limitation, specific embodiments of this invention are shown in the accompanying drawings in which:

FIG. 1 is a fragmentary perspective view illustrating a bracket and coin holding means of the type contemplated by this invention;

FIG. 2 is a sectional view of the bracket taken about the line 2-2 of FIG. 1;

FIG. 3 is a sectional view of the bracket taken about the line 3-3 of FIG. 2; and

FIG. 4 is an enlarged sectional view illustrating the bracket with the fixture of FIG. 1 in position.

In coin holding receptacles of the type described in the aforementioned patents, the boxes or bags which receive the coins are provided with a fixture which provides for association of the receptacles with a bracket mounted in the coin operated machine. Once the coins have passed into the receptacles, it is virtually impossible to engage in undetected pilfering since means are provided which prevent removal of the coins from the bag except through authorized openings or by doing obvious damage to the receptacle. There is, however, an avenue available for pilfering by inserting a means between the bracket and fixtures which would prevent passage of the coins into the receptacle.

It has specifically been found that even a very small opening provided between the top of the fixture and the bottom surface of the bracket will permit insertion of an instrument which will block passage of coins into the receptacle. For example, in the case of the aforementioned patents, a thin card could be inserted which would cause all coins to collect at the bottom of the bracket coin passage while preventing the coins from moving into the fixture coin passage. An attendant could then return to the machine and take the coins which had collected. By removing the card at this time, additional coins would then collect in the receptacle so that it would be very difficult to determine that pilfering had taken place.

The construction of this invention represents an improvement over the coin receptacles previously patented in that pilfering of the type referred to can be prevented. In the drawings, FIG. 1 illustrates a coin receptacle in the form of a bag 10. The bag has a rectangular-shaped block 12 attached thereto. The specific design illustrated is similar to the design shown in U.S. Pat. No. 3,298,602.

10 A bracket 14 is provided with a back wall 16 defining openings 18 whereby the bracket can be secured to a coin operated machine. This bracket is fixed in place immediately beneath the coin chute of the machine so that all coins inserted in the machine will fall into the funnel opening 20 defining the coin passage of the bracket.

15 The bracket also includes a pair of opposed channels 22. The inturned flanges of these channels are adapted to be received in the slots 24 defined by the fixture 12. The shoulder portions 26 of the fixture are received in the channels whereby the fixture can slide into position with respect to the bracket.

20 An arm 28 is attached to the bracket, and this arm includes an angularly disposed end portion 30 and a bent-in portion 32. As the fixture 12 slides inwardly with respect to the bracket, 25 the fixture will bear against the surface of the portion 30 and will bend the arm 28 outwardly. When the fixture has been moved into position, the inturned portion 32 will snap in to lock the fixture in place. The arm 28 therefore functions as a means which will indicate to an attendant that the fixture is 30 properly aligned with respect to the bracket.

25 As best shown in FIG. 4, the fixture 12 includes a coin passage 34 having a funnel shaped entrance 36. The opening to the coin passage of the fixture is substantially rectangular in shape defining two long sides and two relatively narrow sides.

30 It will be noted that the fixture and bracket coin passages are in alignment when the fixture is in place so that coins inserted in the machine will pass through the coin chute of the machine through the respective passages, and then into the coin bag.

35 It will be noted that a slight gap 38 is defined between the underside of the bracket and the top surface of the trailing edge of the fixture. The presence of this gap in structures of the type described in the aforementioned patents provides an opening into which a thin card or sheet could be inserted. This 40 will effectively block the opening to the coin passage of the fixture whereby coins inserted in the machine would collect in the coin passage of the bracket rather than falling into the coin receptacle.

45 The instant invention provides a downturned lip 40 formed as an integral part of the sheet or plate 42 which defines a transversely extending portion as well as the channels for the bracket. This downturned lip effectively blocks insertion of any instrument such as a card or sheet into the coin passage. Even if a card could be forced beyond the point of contact of the fixture with the lip 40, then the card would be bent downwardly along the incline of the funnel opening 36 whereby it would not be effective to block the passage.

50 In order to provide for insertion of the fixture in the bracket, relieved portion 44 is formed in the fixture. This relieved portion extends along the leading edge of the fixture, and it provides clearance for the lip as the fixture is inserted in the bracket. The modification of the fixture and bracket in the manner described provides an ideal combination which greatly improves the characteristics of the structures. It will be 55 noted in this connection that the lip 40 serves an additional

function as a stop means. Thus, the lip will cooperate with the arm 28 with respect to properly aligning the fixture relative to the bracket.

It will be understood that various changes and modifications may be made in the above described construction which provide the characteristics of this invention without departing from the spirit thereof particularly as defined in the following claims.

I claim:

1. In a removable coin holding means for association with a coin operated construction, said construction including a bracket having a plate defining a transversely extending portion and opposed channels extending downwardly from said transversely extending portion, and said coin holding means including a fixture formed of a solid block of material with shoulders defined by the fixture for receipt in said channels for slideably attaching the fixture to the bracket beneath said transversely extending plate portion, said bracket defining a coin passage with the lower end of said passage comprising an opening defined by said transversely extending plate portion, and said fixture defining a coin passage for the passage of coins into said coin holding means, the upper end of said fixture passage comprising a rectangular opening adapted to be

aligned with the opening at the bottom of the bracket passage when the fixture is attached to the bracket, the improvement comprising a downturned lip formed in said transversely extending plate portion at the edge thereof which defines the rear portion of said bracket opening, a relieved portion defined by said fixture adjacent the forward edge of the fixture opening whereby said lip will be cleared by said fixture as the fixture slides into the bracket, said relieved portion extending completely across one long side of said rectangular opening and wherein said lip is coextensive with the opposite long side of said rectangular opening, and wherein said lip abuts against the trailing edge of the fixture opening when the fixture is positioned in the bracket, said lip serving to block access to the coin passage through the space defined between the bracket and fixture, and also serving as a stop means positioning the fixture relative to the bracket, and including a resilient arm secured to said bracket and extending outwardly beneath the channels on at least one side of the bracket, and wherein said fixture bears against the arm during insertion of the fixture in the bracket, said arm resiliently holding the fixture in place.
